UNITED STATES PATENT OFFICE

2,445,442

CIRCUIT INTERRUPTER

Winthrop M. Leeds, Forest Hills, and Robert E. Friedrich, Pittsburgh, Pa., assignors to Westinghouse Electric Corporation, East Pittsburgh, Pa., a corporation of Pennsylvania

Application August 31, 1944, Serial No. 552,132

9 Claims. (Cl. 200—150)

1

This invention relates to circuit interrupters in general and, more particularly, to arc extinguishing structures therefor.

A general object of our invention is to provide an improved circuit interrupter in which interruption of the circuit passing therethrough is obtained in an improved manner.

Another object is to provide a circuit interrupter of the type establishing both a pressure-generating arc and an interrupting arc, and to provide an improved interrupting structure adjacent the pressure-generating break to facilitate low current interruption.

Another object is to provide a circuit interrupter of the foregoing type in which both a first and second piston means are provided to facilitate circuit interruption. Preferably the first piston means has the arcing pressure equalized on both sides thereof to be operative both during low and high current interruption; whereas, the second piston means is preferably of the type which is operative only during low current interruption and may be used for flushing purposes during high current interruption.

Another object is to provide an improved circuit interrupter in which improved operating mechanism is provided to charge piston means associated therewith.

Further objects and advantages will readily become apparent upon a reading of the following specification taken in conjunction with the drawings, in which:

Figure 1 is an elevational view of a complete circuit interrupter embodying our invention and shown in the closed circuit position;

Fig. 2 is an enlarged vertical sectional view through the left-hand arc extinguishing unit of Fig. 1, the parts being shown in the partly open circuit position;

Fig. 3 is a fragmentary vertical sectional view taken substantially on the line III—III of Fig. 2;

Fig. 4 is a sectional view taken substantially on the line IV—IV of Fig. 2; and

Fig. 5 is a sectional view taken substantially on the line V—V of Fig. 2.

Referring to the drawings and more particularly to Fig. 1 thereof, the reference numeral 1 designates a tank in which a suitable arc extinguishing fluid 2, in this instance circuit breaker oil, fills the tank to the level 3. Depending from the cover 4 of the tank 1 are two insulating bushings 5, 6 through which extend terminal studs 7, 8. Threadedly secured to the lower ends of the terminal studs 7, 8 are contact feet 9, 10 which support identical arc extinguishing units gener-

2

ally designated by the reference numeral 11. A conducting bridging member 12 reciprocally operable in a vertical direction by an insulating operating rod 13 serves to electrically interconnect the two arc extinguishing units 11 in the closed circuit position of the interrupter as shown in Fig. 1.

Referring to Fig. 2 it will be observed that the contact foot 9 is formed as an extension of a suitably shaped casting 14, the interior of which forms a housing for contact structure more fully described hereinafter. A pressure-generating contact 16 cooperates with an intermediate contact 17 to establish a pressure-generating arc 18 within a pressure-generating chamber or passage 64 as shown more clearly in Figs. 2 and 3. The pressure-generating contact 16 has a hole 19 formed therein which is guided by an extension 20 threaded into the casting 14. A conductor 21 electrically interconnects the pressure-generating contact 16 with the casting 14.

Two pins 22, only one of which is shown in Fig. 2, are secured to the contact 16 and pass through slots 23 formed through the legs 24 of a bifurcated member 25 pivotally mounted at 26 and actuated externally of the unit 11 by two integrally formed actuating arms 27, only one of which is shown in Fig. 2. The arms 27 have slots 28 through which passes a pin 29. The pin 29 passes through an elongated slot 30 provided in an insulating operating rod 31. A compression spring 32 encircles the rod 31 and is disposed between a flange 33 integrally formed with the rod 31 and the arms 27. In the closed circuit position of the interrupter the compression spring 32 provides the requisite contact pressure between the several contacts. A compression spring 34 has its upper end seated against an extension 35 of the casting 14, and has its lower end resting on a flange 36 integrally formed with rod 31. Thus it will be observed that the spring 34 biases the rod 31 downwardly.

Fixed to and movable with the rod 31 is a first piston member 37 operable within a piston chamber 38 defined by a cylindrical member 39. The piston member 37 moves downwardly during the opening stroke to send oil through the passage 40 and through two inlet passages 41 toward the pressure-generating arc 18.

50 The composite plate structure forms an orifice 42 adjacent each inlet passage, thereby causing the oil to flow through the inlet passages 41 through the orifices 42 thus contacting the pressure-generating arc 18. The pressure created at 55 the pressure-generating arc 18 acts through ex-

haust passages 43 and downwardly through a vertical flow passage 44 through a plurality of inlet passages 45 toward an interrupting arc 46 drawn between the intermediate contact 17 and the lower movable contact 47 within an interrupting chamber 65. This fluid passes through orifices 42 to exhaust out venting passages 48 more clearly shown in Fig. 5.

Associated with the lower movable contact 47 is a second piston member 49 operable within a piston chamber 50 defined by a cylindrical member 51. The upper end of the piston chamber 50 is vented to the region exteriorly of the unit 11 by vent passages 52, 53 more clearly shown in Fig. 3. Consequently, during high current interruption the piston member 49 may be maintained in its raised position against the biasing action of a compression spring 54 tending to bias the piston member 49 downwardly. When the piston member 49 does move downwardly it forces oil to flow upwardly through the passages 55 through check valves 56 and through the inlet passages 48 towards the interrupting arc 46.

Check valves 57 are also provided to allow clean oil to be drawn in through vents 58 when piston 49 is raised during a closing operation, check valves 58 blocking back flow from passages 44 and 45. A compression accelerating spring 59 has its upper seat against a plate 60 and has its lower seat against a flange 61 integrally formed with the contact 47. The conducting bridging member 12 serves during the closing stroke to operate both the lower movable contact 47 and the operating rod 31 to thereby effect an engagement between the several contacts.

It will be observed that the arcing pressure is applied to both the top and bottom of the piston member 37. Thus the piston member 37 is a circulating piston and is operable both during low and high current interruption. The piston member 49, on the other hand, may be stalled during high current interruption by the arcing pressure, and is operable thereafter to flush contaminated oil out of the vents 48 upon a subsidence of pressure within the unit 11.

Circuit interrupters of the type establishing both a pressure-generating arc and an interrupting arc have maximum interrupting effectiveness on low currents such as magnetizing and line-charging currents when mechanically driven pistons are used to supplement the normal flow. Preferably also the arc in the pressure break as well as the interrupting arc at the main break is subjected to deionizing oil flow. Where one piston is used to drive oil into the two breaks in series a very high driving pressure is required. This invention covers a novel method of utilizing two pistons, a circulating piston attached to the operating rod 31 sending oil through the upper pressure break while a second piston 49 is used to supplement the oil flow in the main break. The check and intake valves 56, 57 assure unidirectional flow of clean oil into the unit 11 by operation of the lower piston 49. On high current interruption this piston 49 may be stalled by high back pressure, but subsequent flushing takes place after the pressure falls.

It is to be noted that the upper circulating piston 37 is acted upon by arc pressure on both top and bottom. This balancing effect permits the piston 37 to be rigidly attached to the operating rod 31 without having the motion appreciably slower on high current than on low current interruption. In fact, the high current perform-

ance is improved by keeping fresh oil in closer proximity to the pressure-generating arc.

The arrangement herein shown has proved very effective on tests. Charging currents from 45 to 180 amperes at 68 kv. across one unit 11 were interrupted without restriking.

In the patent application filed May 27, 1943, Serial No. 488,624, now United States Patent 2,424,343, issued July 22, 1947, to Roswell C. Van Sickle, Robert E. Friedrich and Francis J. Fry and assigned to the assignee of the instant application there is disclosed a circuit interrupter similar in construction to the foregoing type in which a circulating piston is provided surrounding the intermediate contact and having the arcing pressure equalized on both sides thereof to render the same operative both during high and low current interruption.

The broad concept of jetting fluid toward the pressure-generating break is disclosed and claimed in United States patent application filed May 28, 1943, Serial No. 488,847 by Winthrop M. Leeds, now United States Patent 2,422,569 issued June 17, 1947, and assigned to the assignee of the instant application.

In the closed circuit position of the interrupter as shown in Fig. 1, the electrical circuit there-through comprises terminal stud 7, contact foot 9, casting 14, conductor 21, pressure-generating contact 18, intermediate contact 17, lower movable contact 47, conducting bridging member 12, through the right-hand unit 11 in an identical manner to the right-hand terminal stud 8.

To open the circuit passing through the interrupter the operating rod 31 is moved downwardly by suitable mechanism, not shown. This lowers the bridging member 12 to permit the compression spring 59 to cause a separation between the contacts 17, 47 to establish an interrupting arc 46. Simultaneously, the bridging member 12 permits downward movement of the rod 31 to take place rotating the bifurcated member 25 and causing a separation between the contacts 18, 17 to establish a pressure-generating arc 18. The two arcs are drawn substantially simultaneously. Pressure created at the pressure-generating arc 18 assisted by the circulation of oil caused by the movement of the piston 37 effects during high current interruption an extinction of the interrupting arc 46.

During low current interruption the piston 49 moves and assists the piston 37, the piston 37 tending to effect the extinction of the pressure-generating arc 18 and the piston 49 tending to effect extinction of the interrupting arc 46. The check valves 56, 57 insure that the oil flow will be in the right direction. Following extinction of the arcs and a consequent breaking of the circuit through the interrupter, the bridging member 12 separates from the disconnect fingers 62 provided at the lower end of the contact 47 to effect an isolating gap in the circuit as shown more clearly in Fig. 1.

During the closing operation the bridging member 12 moves upwardly sliding between the disconnect fingers 62 and causing a raising of both the movable contact 47 and the operating rod 31. The contact 47 makes engagement with the intermediate contact 17 at substantially the same time that the pressure-generating contact 18 makes contact with the intermediate contact 17, the compression spring 32 providing the requisite contact pressure between the several contacts.

Although we have shown and described a spe-

cific structure, it is to be clearly understood that the same was merely for the purpose of illustration and that changes and modifications may readily be made therein by those skilled in the art without departing from the spirit and scope of the appended claims.

We claim as our invention:

1. In a circuit interrupter, means defining a pressure-generating chamber and an interrupting chamber, means for establishing a pressure-generating arc within the pressure-generating chamber and an interrupting arc within the interrupting chamber, the pressure-generating arc forcing fluid toward the interrupting arc to effect the extinction thereof, means forming at least two inlet passages at different levels leading toward the pressure-generating arc, means forming two orifices adjacent the pressure-generating arc through which it is drawn, one orifice associated with each inlet passage, and means for forcing fluid through the inlet passages toward the pressure-generating arc.

2. In a circuit interrupter, means defining a pressure-generating chamber and an interrupting chamber, means for establishing a pressure-generating arc within the pressure-generating chamber and an interrupting arc within the interrupting chamber, the pressure-generating arc forcing fluid toward the interrupting arc to effect the extinction thereof, means forming at least two inlet passages at different intervals leading toward the pressure-generating arc, means forming two orifices adjacent the pressure-generating arc through which it is drawn, one orifice associated with each inlet passage, and piston means for forcing fluid through the inlet passages toward the pressure-generating arc.

3. In a circuit interrupter, means defining a pressure-generating chamber and an interrupting chamber, a pressure-generating contact separable from an intermediate contact to establish a pressure-generating arc within the pressure-generating chamber, a movable contact separable from the intermediate contact to establish an interrupting arc within the interrupting chamber, means forming at least two inlet passages at different levels leading toward the pressure-generating arc, means forming an orifice associated with each inlet passage through which the pressure-generating arc is drawn, operating means for the pressure-generating contact, and piston means actuated by the operating means for forcing fluid through the inlet passages toward the pressure-generating arc.

4. In a circuit interrupter, means defining a pressure-generating chamber and an interrupting chamber, a pressure-generating contact separable from an intermediate contact to establish a pressure-generating arc within the pressure-generating chamber, a movable contact separable from the intermediate contact to establish an interrupting arc within the interrupting chamber, means forming at least two inlet passages at different levels leading toward the pressure-generating arc, means forming an orifice at an intermediate level associated with each inlet passage through which the pressure-generating arc is drawn, operating means for the pressure-generating contact, piston means actuated by the operating means for forcing fluid through the inlet passages toward the pressure-generating arc, and means for equalizing the arcing pressure on both sides of the piston means.

5. In a circuit interrupter of the fluid flow type, means defining a pressure-generating chamber,

means for establishing a pressure-generating arc within the pressure-generating chamber, means defining an interrupting chamber, means for establishing a serially related interrupting arc within the interrupting chamber, means forming a plurality of orifices at a plurality of different levels through which the pressure-generating arc is drawn, means forming an inlet passage on one side of a plurality of said orifices leading toward

5 10 the pressure-generating arc, means defining at least one exhaust passage leading away from the pressure-generating arc between two orifices at an intermediate level, the exhaust passage leading toward the interrupting arc within the interrupting chamber, and means for forcing fluid under pressure through the inlet passages and longitudinally of the pressure-generating arc through the plurality of orifices to exhaust away from the pressure-generating arc through the exhaust passage.

20 15 25 30 35 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000

7. In a circuit interrupter of the fluid flow type, means defining a pressure-generating chamber, means for establishing a pressure-generating arc within the pressure-generating chamber, means defining an interrupting chamber, means for establishing a serially related interrupting arc within the interrupting chamber, means forming a plurality of orifices at a plurality of different levels through which the pressure-generating arc is drawn, means forming an inlet passage on one side of a plurality of said orifices leading toward the pressure-generating arc, means defining at least one exhaust passage leading away from the pressure-generating arc between two orifices at an intermediate level, the exhaust passage leading toward the interrupting arc within the interrupting chamber, and piston means for forcing fluid under pressure through the inlet passages and longitudinally of the pressure-generating arc through the plurality of orifices to exhaust away from the pressure-generating arc through the exhaust passage.

8. In a circuit interrupter of the fluid flow type, means defining a pressure-generating chamber, means for establishing a pressure-generating arc within the pressure-generating chamber, means defining an interrupting chamber, means for establishing a serially related interrupting arc within the interrupting chamber, means forming a plurality of orifices at a plurality of different levels through which the pressure-generating arc is drawn, means forming an inlet passage on one

side of a plurality of said orifices leading toward the pressure-generating arc, means defining at least one exhaust passage leading away from the pressure-generating arc between two orifices at an intermediate level, the exhaust passage leading toward the interrupting arc within the interrupting chamber, piston means for forcing fluid under pressure through the inlet passages and longitudinally of the pressure-generating arc through the plurality of orifices to exhaust away from the pressure-generating arc through the exhaust passage, and means for equalizing the arcing pressure on both sides of the piston means.

9. In a circuit interrupter of the fluid type, means at least partially of insulation forming a pressure-generating arc passage, means for establishing a pressure-generating arc within the arc passage, the arc passage having formed therein a plurality of pockets at spaced intervals along the arc passage, means forming a plurality of inlet passages leading into at least two pockets so that fluid may flow through the inlet passages into the pockets and be directed toward the pressure-generating arc at spaced intervals therealong, means defining an interrupting chamber, means for establishing an interrupting arc within the interrupting chamber, means forming an exhaust passage leading away from the pressure-generating arc passage at an intermediate interval and

10 15 20 25 30 directed into the interrupting chamber, piston means for forcing fluid under pressure first through the plurality of inlet passages toward the pressure-generating arc, then out of the pressure-generating arc passage through the exhaust passage and in serial manner on into the interrupting chamber, and means for equalizing the arcing pressure on both sides of the piston means.
